UNITED STATES PATENT OFFICE.

JOHN H. IRWIN, OF PHILADELPHIA, PENNSYLVANIA.

LAMP-BURNER.

Specification forming part of Letters Patent No. 99,443, dated February 1, 1870.

To all whom it may concern:

Be it known that I, JOHN H. IRWIN, of Philadelphia, in the county of Philadelphia and State of Pennsylvania, have invented certain Improvements in Kerosene-Burners, of which the following is a specification:

My invention consists in the combination of a jacket or shield and cone with a deflector-plate at the top of the wick-tube, so that the air to supply the flame is controlled, as more fully hereinafter described; and it further consists, in combination with the shield and cone, of a perforated guide or support, which acts as a guide to place the cone and shield in proper position and hold them there.

In the accompanying drawings, Figure 1 is a perspective view of my invention; Fig. 2, same with cone and shield removed; Fig. 3, vertical central section of Fig. 1 with the oil-reservoir added.

This invention relates to an improvement in the construction of burners designed to be used in connection with an air-chamber above the oil-pot; and it consists in constructing the burner with an outer imperforate jacket fitted at its lower end to engage with a collar on the top of said air-chamber, while the burner is fitted in the usual manner to a socket in the oil-pot, and the burner has therefore two supports.

It also consists in a mode of constructing the parts of the burner so that the said jacket or shield shall act as a gage to insure the proper relative position of the wick-tube and cone; and it further consists in the deflecting-plate located at the top of the wick-tube.

That the construction and operation of this device may be fully understood, I will particularly describe it.

G is an air-chamber located above the oil-pot, and through this chamber the air passes to reach the flame below the cone. Said chamber G has a central orifice, which encircles the socket in the oil-pot, and said orifice is surrounded by the collar H, to receive the lower edge of the jacket of the burner, which thereby is supported not only in the oil-pot socket, but at the outer edge of the frame or jacket also, and is therefore more securely held in place than if supported by the socket only.

The perforated frame or casing B is fitted at its lower extremity to a socket in the top of the oil-pot, and at its upper edge it expands outwardly and joins the jacket A at a.

The wick-tube C and the ordinary wick-riser

are both attached to the frame B in the ordinary way, and the cone A' rises above the wick-tube in the usual manner.

I represent screws, or their equivalents, which may be attached to secure the jacket A to the collar H, if it is thought to be necessary.

At the upper end of the wick-tube C, I attach a deflecting-plate, D, by which the currents of air ascending from the air-chamber through the perforations in the frame B are turned away from the base of the flame and against the inner surface of the cone A', by which they are brought back to the flame at a higher point, as indicated by the arrows.

As a process of manufacture, it is more convenient to form the jacket A and cone A' in one piece and separate from the frame B.

The shoulder a is fitted to the upper edge of the frame B, and, when the parts are in position, acts as a gage to cause the upper end of the wick-tube to come into proper position in reference to the slot F at the top of the cone. This is made necessary because it is practically very difficult to manufacture the oil-pot with the burner-socket located exactly in the center of the orifice surrounded by the collar H, and without an adjusting-gage either the upper end of the wick-tube would be improperly located in respect to the slot F, or the opening in the top of the air-chamber would be imperfectly closed.

Having now described my invention, what I claim as new is—

1. A lamp-burner provided with an outer imperforate jacket, A, fitted at its lower edge to engage with a collar, H, or its equivalent, to give the burner two supports, as set forth.

2. The jacket A and cone A', formed of one piece, with a shoulder, a, in combination with the perforated frame B, fitted to said shoulder for the purpose of gaging the adjustment of the wick-tube, as set forth.

3. A burner with a jacket, A, cone A', and deflecting-plate D at the top of the wick-tube, all constructed and arranged substantially as described.

4. A burner constructed with the jacket A and perforated frame B, substantially as described, in combination with the air-chamber G, provided with a collar, H, or equivalent, as set forth.

J. H. IRWIN.
